UNITED STATES PATENT OFFICE.

JOHN DE YOUGH, OF NEW YORK, N. Y.

DESIGN FOR A CATALOGUE-COVER.

SPECIFICATION forming part of Design No. 16,173, dated July 21, 1885.

Application filed March 7, 1885. Term of patent 14 years.

To all whom it may concern:

Be it known that I, JOHN DE YOUGH, of the city, county, and State of New York, have invented and produced a new Design for Catalogue-Covers and Pamphlets, of which the following is a specification.

In the accompanying drawings, illustrating my invention and forming a part of this specification, Figure 1 is a view of a leaf of the cover, showing my design in shape and configuration; and Fig. 2 is a similar view of the two sides of the cover open.

The leading feature of my design consists in a flat cover having parallel top and bottom edges and parallel side edges, with two opposite corners truncated and having parallel edges, and the cover having lines traced thereon which produce the outline figure of a right-line parallelopiped, substantially as seen in the drawings.

More particularly describing the design with reference to the drawings, the letter A designates the side of the cover, with parallel top and bottom edges, a a' , and parallel side edges, a^2 a^2 , the opposite diagonally-arranged corners of the cover being truncated to give the requisite angle, as seen at a^3 a^3 . Lines are produced to border the edges of the cover, and lines b b' , parallel to the top and bottom and to the side edge of the cover and at right angles to each other, are produced from the upper point of each truncated corner, which

said lines terminate in their point of intersection. Similar lines, c c' , may be produced intermediate of the lines b b' and the edges of the cover and the point of intersection of the innermost lines, and the corner of the cover connected by a right line, d , produced parallel with the lines of the truncated corners, thus producing the figure of a right-line parallelopiped, or, as is particularly intended, the figure of a rectangular box, and in connection with the intermediate lines of the cover a box with its lid or cover.

What I claim as my invention, and desire to secure by Letters Patent, is—

The design for a catalogue or book cover herein shown and described, the same consisting of a cover having parallel side edges, parallel top and bottom edges, with two opposite corners truncated and having parallel edges, and lines produced on the edge of the cover, and lines produced within the said edges, forming therewith the outlines of a parallelopiped rectangular box.

Signed at 44 West Broadway, New York city, this 21st day of February, 1885, and in the presence of the two witnesses whose names are hereto written.

JOHN DE YOUGH.
